EXPLOSIVE LOADING

John D. Clark, Brentwood, Mo., and Russell C. McKenney, East Alton, Ill., assignors to Olin Mathieson Chemical Corporation, a corporation of Virginia

Application May 12, 1950, Serial No. 161,698

2 Claims. (Cl. 86—20)

This invention relates to the art of filling containers with explosive and more particularly to the loading of shells, small bombs, and other explosive projectiles.

Heretofore, the loading of such projectiles with fusible explosives, such as TNT and mixtures thereof with cyclonite or ammonium nitrate, had been accomplished by melting a large mass of the explosive and then successively filling a number of the projectiles by pouring the molten explosive into the mouth of the cavity within the projectile. Among other difficulties experienced, there has been a tendency for the explosive to adhere to the mouth of the projectile and it has been necessary to manually clean any threads or grooves in the mouth subsequent to the filling operation. Further, air bubbles tended to be trapped within the explosive charge when it solidified. Likewise, such explosives tend to shrink upon cooling from a molten state to solidification and an undesirable cavity or sinkhead is formed at the surface of the explosive as it hardens.

Various devices have been described for the purpose of avoiding such undesirable effects while pouring the molten explosive into the projectile but with such devices it was still the practice to melt a large mass of explosive and control the pouring of such molten explosive by means of valves so that projectiles could be filled on a production basis. The melting and pouring and control by valves of a large mass of explosive is, of course, a hazardous operation. Numerous explosions have resulted from the operation of such valves and it is an object of this invention to provide novel efficient means for loading such projectiles with fusible explosive on a mass production basis without the necessity of melting large masses of the explosives or use of valves. Another object is to provide a method and device for filling containers with explosives free of the disadvantages referred to in the foregoing. Another object is to provide a device facilitating the loading of projectiles with the body of explosive free of undesirable voids and similar imperfections. Another object is to provide a device and method of filling containers with explosive which overcome the disadvantage occasioned by shrinkage of the explosive upon solidification. A further object is to provide a device and method for economically and effectively loading containers with explosives of the type that shrink upon solidification. A still further object is to increase the safety of the operation of loading projectiles with a dense mass of explosive. Still another object is to provide a hopper having improved means for assembly with the container to be filled with explosive and for removal therefrom.

The foregoing objects and advantages, as well as others which may become apparent from the detail description hereinafter are accomplished in accordance with this invention by providing a hopper adapted to be easily inserted into the mouth of the cavity to be filled with explosive and so designed and constructed as to serve as a melting vessel for the charge of particulate explosive for the container and deposit therein a dense charge of the explosive. Inasmuch as the hopper holds only a sufficient amount of explosive

2

to properly load one projectile, only a small amount of explosive need be concentrated in any one location and by utilizing a number of such hoppers production loading of the containers can be accomplished without melting any large mass of explosive. Having indicated in the foregoing in a general way the nature and substance of this invention, there follows a more detailed description of a preferred embodiment thereof with reference to the accompanying drawing in which:

Figure 1 is a top or plan view illustrating a hopper embodying this invention, and

Figure 2 is a longitudinal sectional view of the hopper illustrated in Figure 1.

Referring to Figures 1 and 2, the hopper is formed of vessel or upper chamber 1 of rectangular shape provided with fins 2, a perforate bottom or septum 3, side walls 4 extending below the bottom 3, and a shoulder 5 designed to rest on the upper edge of the lower chamber or funnel-shaped portion 6. The lower chamber 6 terminates in an annular portion or outlet 7 provided with a stop 8 and a resilient gasket 9, which is preferably secured to the annular portion 7.

In operation, the annular portion 7 is pushed into the mouth of the cavity in the projectile 10 to be filled with explosive, with the gasket 9 serving to align the hopper in position by compression between the mouth of the projectile 10 and annular portion 7. The hopper is supported by the stop 8 resting on the edge of the projectile 10 and limiting the extent of insertion. When the hopper-projectile assembly is of such dimension as to be top heavy or unstable, it may be held upright by any suitable means. If, as illustrated, the projectile mouth is internally threaded, as at 11, the gasket 9 prevents explosive from filling in the threads and maintains a snug fit in the mouth of the projectile. To shorten the time required for melting the explosive the hopper-projectile assembly is preheated to a temperature near the melting point of the explosive, say 80° C.—90° C. in the case of TNT, and the vessel 1 is then filled with the particulate explosive. The particulate explosive may be in the form of crystals, or of comminuted, granular, ribbon- or tape-like fragments, or in any other desired form of subdivision. The assembly having the explosive in vessel 1 is then heated at a temperature above the melting point of the explosive until all the explosive has melted and flowed by gravity through the perforations in bottom or plate 3 into the funnel-shaped portion 6 through outlet 7 and into the projectile 10, whereupon it is then cooled. By so melting the explosive and permitting the molten material to flow into the projectile, the melting and flowing occurs as small rivulets or droplets and is sufficiently gentle or gradual to avoid entrapment of air within the explosive mass. A very dense casting of explosive within the projectile is thus obtained. The amount of particulate explosive held by the vessel 1 is sufficient upon being melted to fill not only the projectile but a portion of the lower chamber 6 of the hopper, so that there is a head or riser 12 of explosive therein. Upon solidification of the explosive, the sinkhead or cavitation occurs external of the projectile as at 13. As the projectile fills with explosive the displaced air escapes up through perforations in 3, or, if the perforations are all filled with molten explosive, the air escapes between the top of the funnel-shaped portion 6 and the

sidewall 4 and shoulder 5. If the hopper is so designed that the funnel-shaped portion 6 is not detachable then a suitable air vent is provided below the bottom of perforated plate 3. When the assembly has sufficiently cooled to permit the explosive to solidify the hopper is subjected to a slight lateral movement with respect to the projectile, whereupon the explosive is cleanly severed at the bottom 14 of the hopper. The hopper is then removed from the projectile merely by pulling it out of the

3
mouth. The gasket being rubber-like facilitates the operation.

As illustrated the hopper is so designed as to be readily taken apart by merely lifting the vessel 1 from the funnel-shaped portion 6 which greatly facilitates subsequent cleaning thereof. The riser of explosive in the portion 6 may be readily removed by turning said portion upside down and knocking the riser out. The inner surface of the portion 7 is preferably a truncated cone with its narrowest diameter at the outlet to facilitate removal of the riser. Upon separating the vessel 1 from the portion 6, the perforate bottom 3 of the upper chamber is likewise made easily accessible for cleaning. The vessel 1 and portion 6 need not be made detachable but it is preferred that they be separable to facilitate cleaning and reuse. The vessel 1 may be of rectangular shape, as illustrated, and the fins are utilized to provide more heat exchange surface between the explosive and the source of heat. The time of melting required by the explosive is thereby considerably shortened. The shape need not be exactly rectangular but may be of any desired configuration designed to facilitate transfer of heat to the explosive. The resilient gasket 9 about the annular portion 7 serves a multi-fold purpose in that it facilitates insertion of the portion 7 into the open mouth of the projectile 10 and removal therefrom, and at the same time prevents explosive from entering the threads, if any, existent in the mouth of the projectile. The resilient gasket 9 may be of any suitable rubber-like material such as polyethylene or other suitable plastic, but is preferably made of synthetic rubber and of hollow construction, as illustrated, for greater resilience.

In production, the hoppers and empty projectiles can be assembled and held upright on an automatic conveyer, which carries them successively through a preheating oven where they are preheated to a temperature near the melting point of the explosive to be utilized, then to an explosive charging station where the proper weight of particulate explosive is charged into the vessel 1, then again through an oven of sufficient length and temperature to permit all of the explosive to melt and flow through the perforated bottom 3 of the container, and thence to cooling and disassembling stations, where the hopper is detached from the explosive-charged projectiles. During the melting and conveying operations the individual hopper-projectile assemblies may be so spaced that if one is exploded, adjacent assemblies are not exploded, thus greatly increasing the safety of the operation.

As will be apparent from the foregoing specific embodiment, the method and hopper of this invention facilitate the safe loading of explosive containers with cast dense charges of explosive within the container. It is to be understood that the embodiment of the present invention as shown and described is only illustrative and that many changes may be made therein without departing from the spirit and scope of the invention as set forth in the following claims.

Having thus described the invention what is claimed and desired to secure by Letters Patent is:

1. The improved method of filling projectiles with a dense charge of fusible explosive substantially devoid of entrapped air pockets which comprises assembling with said projectile a filling device having a hopper, a funnel shaped portion depending therefrom and having a dis-

charge end adapted to be detachably secured to the filling aperture of the projectile, a resilient gasket about said discharge end and a perforated plate separating the hopper from the funnel shaped portion, said assembling being achieved by inserting said discharge end in said aperture with said gasket compressed between the wall of the projectile and the wall of said discharge end; placing just sufficient explosive in particulate form on said perforated plate to fill the projectile and only a portion of the funnel shaped portion of the filling device with molten explosive; placing the assembly in a heated atmosphere and heating the explosive until it gradually melts and flows in small rivulets and droplets through the perforations in said plate and through the funnel shaped portion into the projectile thereby displacing the air in the projectile through the perforated plate and filling the projectile and a portion of the funnel shaped portion of the filling device; cooling the assembly until the resulting cast charge of explosive in the projectile and said funnel shaped portion solidifies; and thereafter moving said funnel laterally with respect to the projectile thus severing the explosive in the projectile from that in the said funnel shaped portion.

2. A filling device for filling a projectile having a filling aperture surrounded by a casing, said filling device being adapted to be charged with particulate explosive and, upon heating, to discharge molten explosive into said projectile with substantially complete displacement of the air in said projectile, said filling device comprising a hopper with heat exchange means, a funnel shaped conduit means depending from said hopper and having a discharge end having a resilient gasket thereabout and within the filling aperture of the projectile, and an annular flange adapted to rest on the end of the projectile, said discharge end being detachably secured in said filling aperture of said projectile with said flange resting on said casing and with said gasket compressed between said casing and said conduit means, thereby preventing molten explosive from creeping between said discharge end and the casing about said aperture as the projectile is filled therewith, and a perforated plate separating the hopper from said conduit means adapted to support an explosive in particulate form but to permit, upon heating, molten explosive to flow through the perforations in small rivulets and droplets and to drop into said conduit and projectile and to substantially completely displace the air as the projectile and a portion of the conduit is filled with molten explosive, said gasket permitting free movement of said conduit relative to said projectile to permit separation of said filling device from said projectile after cooling and solidification of the explosive by breaking apart the portions of explosive in said projectile and in said conduit.
